UNITED STATES PATENT OFFICE.

NIELS A. CHRISTENSEN, OF MILWAUKEE, WISCONSIN.

STARTING APPARATUS FOR INTERNAL-COMBUSTION ENGINES.

1,253,466.

Specification of Letters Patent. Patented Jan. 15, 1918.

Application filed November 25, 1912. Serial No. 733,320.

To all whom it may concern:

Be it known that I, NIELS A. CHRISTENSEN, a subject of the Kingdom of Denmark, residing at Milwaukee, in the county of Milwaukee and State of Wisconsin, have invented certain new and useful Improvements in Starting Apparatus for Internal-Combustion Engines, of which the following is a specification, reference being had to the accompanying drawing, forming a part thereof.

This invention relates more particularly to means for generating current for the ignition of the explosive charges in connection with starting apparatus having a dual system of ignition.

Its main objects are to dispense with batteries and to avoid the trouble, uncertainty and annoyance incident to their use in such apparatus, and generally to improve the construction and operation of apparatus of this class.

It consists in the construction, arrangement and combination of parts as herein-after particularly described and defined in the appended claims.

In the accompanying drawing like characters designate the same parts in the several figures.

Figure 1 is a diagrammatic view of starting apparatus embodying the invention; Fig. 2 is an enlarged end elevation and section on the line 2—2, Fig. 1, of the starting magneto and motor; and Fig. 3 is a diagram showing the several positions of the driver's valve which controls the operation of the starting apparatus.

Referring to Fig. 1, the apparatus comprises in its preferred embodiment, a reservoir 1 for compressed air or other starting fluid, a carbureter 2, distributing valve mechanism 3, a compressor 4, a gasolene tank 5 connected with the carbureter 2, and a driver's valve 6, for supplying the engine with an uninterrupted series of successive compressed and carbureted charges of fluid during the normal firing strokes only of the engine piston or pistons. The apparatus also includes a dual system of ignition, and comprises a main magneto 7, actuated by the engine, a starting magneto 8, operative independently of the engine, a fluid pressure motor 9, for actuating the magneto 8, an induction coil and switch 10, and a timer

or circuit interrupter 11 and a distributor 12 associated with the main magneto 7.

The engine, of which only portions of the cylinders are shown, is provided with spark plugs 13 both for starting and the normal operation of the engine.

The reservoir 1 is connected by a pipe 14 with the driver's valve 6, which in turn is connected by a pipe 15 with the inlet of the motor 9. The outlet of the motor is connected by a pipe 16 with the carbureter 2, from which the compressed carbureted air is delivered to the distributing valve 3. The distributing valve 3 is connected by pipes 17 with the several cylinders of the engine through check valves 18, which close outwardly from the cylinders.

The compressor 4 is connected by a discharge pipe 19 with the driver's valve 6, and the gasolene tank 5 is connected by a pipe 20 with the carbureter 2. The distributing valve mechanism 3 and the compressor 4 are actuated by a shaft or spindle 21, which is connected with the cam or crank shaft of the engine in an unchanging angular relation thereto, so that an uninterrupted succession of compressed carbureted charges will be delivered by the valve mechanism to the several cylinders of the engine through the pipes 17 and check valves 18 during the normal firing strokes only of the pistons. The driver's valve 6 or the manually operated controlling valve which is mounted on the dash of an automobile or in some position conveniently accessible to the driver or operator, has an arm or handle 22 movable as shown in Fig. 3, into three different positions, *a*, *b* and *c*.

In the middle or neutral position *a*, the reservoir 1 is cut off from communication with both the distributing valve mechanism 3 and the compressor 4. When the handle is turned to position *b*, communication is established between the reservoir 1 through pipes 14 and 19, with the compressor 4, which is automatically or manually started if the engine is running, and then forces air through the pipes 19 and 14. The compressor is automatically started when compressed fluid is admitted thereto through its discharge pipe 19 by means of a clutch (not shown) which is shifted into position to connect the crank shaft or movable member of the compressor with the driving spindle

21 by compressed air admitted to a clutch operating piston or member through a branch pipe 23 connected with the pipe 19 and provided with a valve 24. The compressor 5 may also be started manually by a clutch shifting stem or spindle 25.

When the handle 22 is turned from its central position *a*, to position *c*, communication is established between the reservoir 1 and the carbureter 2 and distributing valve mechanism 3, through the pipes 14 and 15, the magneto motor 9, and the pipe 16. When this connection is made, the distributing valve mechanism is automatically started 10 by a fluid pressure operated device (not shown) which connects said mechanism with the spindle 21.

The apparatus thus far described and comprising the carbureter, compressor, distributing valve mechanism and driver's valve for supplying an uninterrupted series of compressed carbureted charges to the engine on the firing strokes of the pistons, is like or similar in construction and operation to 20 that shown and described in United States Letters Patent issued to me, No. 1,185,874, dated June 6, 1916, and No. 1,211,410, dated January 9, 1917, and in my application Serial No. 805,287, filed Dec. 8, 1913, and 25 therefore need not be more particularly shown and described. It may however, be modified in various ways without affecting the operation of the ignition system herein-after described, to which the present invention relates, and with which such charging apparatus coöperates.

The starting magneto motor 9, which is connected in series with the controlling valve 6 and carbureter 2 by the pipes 15 and 16, 30 as shown in Fig. 2, comprises a casing 27, having an inlet passage 28 with which the pipe 15 is connected, and a discharge passage 29, with which the pipe 16 is connected, and a wheel 30 mounted on or connected 35 with the armature shaft of the magneto and formed or provided around its periphery with a series of obliquely disposed buckets 31. The wall of the casing surrounding the wheel 30 is formed or provided on opposite 40 sides with nozzles 32 and 33, connected with the inlet passage 28 and with each other by a passage 34, and each having a number of obliquely disposed jets 35 arranged to deliver the compressed starting fluid on its way 45 from the reservoir 1, to the carbureter and distributing valve mechanism, into the buckets 31 of the wheel 30, and thus rapidly rotate the armature of the magneto 8. Between the nozzles 32 and 33 the casing is 50 formed next to the periphery of the wheel 30 with curved passages 48, which are connected with each other by a passage 49, as indicated by dotted lines in Fig. 2, and one of which communicates with the passage 29. 55 The wheel 30 has a free working fit in the

casing 27 and there is a slight clearance between the inner ends of the nozzles 32 and 33 and the periphery of the wheel.

One terminal of the magneto 8 is grounded as indicated at 36, Fig. 1, and the other terminal is connected by a wire 37 with the switch of the induction coil 10. One terminal of the main magneto 7 is connected by a wire 38 with the switch of the induction coil 10, the primary and secondary windings of 75 which are grounded at one end as indicated at 39.

A wire 40 connecting the coil 10 with the distributor 12, conducts either ~~current~~ *from* the main magneto 7 in the *normal operation* 80 of the engine or current induced by the magneto 8 in the secondary winding of said coil in starting, to said distributor. A wire 41 conducts current from the primary winding of the coil 10 to a part of the interrupter or 85 circuit breaker 11, and a wire 42 grounds the primary circuit of the main magneto 7 when the coil switch is set to operatively connect the magneto 8, coil 10 and distributor 12 for starting.

The terminals of the distributor 12 are connected in the usual manner by wires 43 with the spark plugs 13.

The magneto is provided with a crank 44, as shown in Fig. 1, which is geared in any 95 suitable manner (not shown) with the armature for manually turning it, and generating starting current independently of the motor 9.

The induction coil 10 has, as usual, a 100 switch operating arm or handle 45, and a push button 46 for closing the circuit through a vibrator.

In the operation of the apparatus for starting the engine, the reservoir 1 having 105 been charged with air at the requisite pressure, which may be indicated by a gage 47, Fig. 1, the handle 22 of the valve 6 is turned to position *c*, as indicated in Fig. 3, and the switch arm or handle 45 of the induction coil 10 is turned into position to operatively connect the starting magneto 8, induction coil 10 and distributor 12 and to ground the primary circuit of the main magneto 7. Compressed air being thus admitted to the motor 9, rapidly turns the wheel 30 and the armature of the magneto 8, thereby generating current which, passing through and transformed by the induction coil 10 and subject to the control of the interrupter 11 and distributor 12, produces a spark in that cylinder whose piston is on the firing stroke, and ignites the explosive charge simultaneously admitted to said cylinder by the distributing valve mechanism, 115 as hereinbefore described.

The engine being started, a series of compressed carbureted or explosive fluid charges will be admitted in like manner by the distributing valve mechanism 3 into the engine 120 130

cylinders on the firing strokes of the pistons, and such charges will be ignited by properly timed sparks produced by current supplied from the starting magneto 8, as above explained.

After the engine is well started, the valve handle 22 is turned back to its neutral position *a*, thereby cutting off the supply of compressed fluid from the motor 8, and the distributing valve mechanism 3, and the switch handle 45 of the induction coil 10 is turned into position to cut out the starting magneto 8 and to cut in the main magneto 7. The engine will then run normally, drawing in and compressing in the usual manner on the suction and compression strokes of the pistons, charges of carbureted air or explosive fluid which are ignited on the firing strokes of the pistons by currents supplied from the main magneto 7, while the motor 9 and the distributing valve mechanism 3 of the starting apparatus will remain inactive until they are again brought into service, as above explained.

In place of a magneto, a small dynamo may be used for generating the starting current and the term "magneto" as employed in the following claims, is intended to include any equivalent or suitable type of electric generator.

Various changes in the construction and arrangement of parts of the ignition system as well as of the fluid charging apparatus may be made without departing from the principle and scope of the invention.

I claim:

1. In starting apparatus for internal combustion engines the combination of a reservoir for compressed fluid, a magneto having an actuating connection with the engine for supplying current thereto during its normal operation, a magneto, operative independently of the engine for supplying starting current thereto, means common to both magnetos for timing the delivery to the engine of current generated by either magneto on the firing strokes of the piston, and an incased fluid pressure motor operatively connected with the starting magneto and having a fluid supply connection with said reservoir and an outlet connection with the engine.

2. In starting apparatus for internal combustion engines the combination of a reservoir for storing fluid under pressure, a magneto having an actuating connection with the engine for supplying current thereto during its normal operation, a magneto operative independently of the engine for supplying starting current thereto, means common to both magnetos for timing the delivery to the engine of current generated by either magneto on the firing strokes of the piston, an incased fluid pressure motor operatively connected with the starting mag-

neto and having a valve-controlled fluid supply connection with said reservoir and an outlet connection with the engine, and means for manually operating the starting magneto.

70

3. In starting apparatus for internal combustion engines the combination of a reservoir for compressed fluid, a distributing valve actuated by the engine and timed to deliver a succession of charges from the reservoir to an engine cylinder on the firing strokes of the piston, a magneto operative independently of the engine for supplying starting current thereto, an incased fluid pressure motor operatively connected with said magneto and having a fluid supply connection with said reservoir and a carburetor connected with the engine and with the outlet of the motor.

75

4. In starting apparatus for internal combustion engines the combination with a reservoir for compressed fluid, a distributing valve actuated by the engine and timed to deliver a succession of charges from said reservoir to an engine cylinder on the firing strokes of the piston, means for carbureting the fluid, a magneto operative independently of the engine for supplying starting current thereto, and an incased fluid pressure motor operatively connected with the magneto and having a valve controlled fluid supply connection with the reservoir and an outlet connection with the engine.

80

85

90

95

5. In starting apparatus for internal combustion engines the combination of a reservoir for compressed fluid, a distributing valve actuated by the engine and timed to deliver successive charges of fluid from the reservoir to an engine cylinder on the firing strokes of the piston, a magneto operative independently of the engine for supplying starting current thereto, a fluid pressure motor operatively connected with said magneto and connected with the fluid supply pipe leading from the reservoir to the engine, and a driver's valve in said supply pipe controlling the supply of starting fluid from said reservoir to the engine and the operation of said magneto.

100

105

110

6. In starting apparatus for internal combustion engines the combination of a reservoir for compressed fluid, a distributing valve actuated by the engine and timed to deliver successive charges of fluid from the reservoir to an engine cylinder on the firing strokes of the piston, a carburetor in the connection between the reservoir and engine, a magneto operative independently of the engine for supplying starting current thereto, an incased fluid pressure motor operatively connected with the magneto and having fluid supply and outlet connections with the conduit leading from the reservoir through the distributing valve to the engine, and a valve controlling the supply of com-

115

120

125

130

pressed fluid through the motor and distributing valve to the engine.

7. In starting apparatus for internal combustion engines the combination of a reservoir for compressed fluid, a distributing valve actuated by the engine and timed to deliver successive charges of fluid from the reservoir to an engine cylinder on the firing strokes of the piston, a magneto operative independently of the engine for supplying starting current thereto, a fluid pressure motor operatively connected with the magneto and having a fluid supply connection with the reservoir, a compressor

having an actuating connection with the engine, and a fluid delivery connection with the reservoir, and a manually operated valve controlling the supply of fluid from said reservoir to the distributing valve and to the magneto motor and the delivery of fluid from the compressor to the reservoir. 15
